ADJUSTABLE OTTOMAN

Murray Langbaum, East Hills, N.Y., assignor to Nova Products Corp., Brooklyn, N.Y., a corporation of New York

Filed July 27, 1961, Ser. No. 66,099

Term of patent 14 years

(Cl. D15—8)

FIG. 1

FIG. 2

FIG. 3

FIG. 1 is a three-quarter perspective view of an ottoman showing my new design, the adjustable top member being shown in lowered position;

FIG. 2 is a view similar to FIG. 1 but with the adjustable top member shown in a raised position; and

FIG. 3 is a side elevational view of the ottoman of FIG. 2.

I claim:

The ornamental design for an adjustable ottoman, as shown.
